(57) **CLAIM**

The ornamental design for a handpiece for skin perforation as shown and described.

DESCRIPTION

1. Handpiece for skin perforation

FIG. 1.1 is a perspective view of a handpiece for skin perforation;

FIG. 1.2 is a front view thereof;

FIG. 1.3 is a back view thereof;

FIG. 1.4 is a top view thereof;

FIG. 1.5 is a bottom view thereof;

FIG. 1.6 is a left view thereof; and

FIG. 1.7 is a right view thereof.

The present design is a handpiece used by mounting it on the main body of a skin perforator for skin transplantation, with a display installed on the upper part indicating the perforation status.
